UNITED STATES PATENT OFFICE.

TITO LIVIO CARBONE, OF CHARLOTTENBURG, GERMANY.

ARC-LAMP.

1,017,641.

Specification of Letters Patent.

Patented Feb. 13, 1912.

Application filed February 21, 1910. Serial No. 545,090.

To all whom it may concern:

Be it known that I, TITO LIVIO CARBONE, a citizen of the Swiss Republic, residing in Charlottenburg, near Berlin, Germany, have 5 invented certain new and useful Improvements in Arc-Lamps, of which the following is a specification.

My present invention refers to electric arc-lamps of the kind usually employed 10 where economy in the consumption of electrodes is looked for. To attain this object it is necessary to prevent access of fresh air to the arc by closing the globe, so that the oxygen contained therein when the lamp is 15 started is quickly consumed and the combustion of the electrodes thereby very much retarded. As is well known in the art, great difficulty with lamps of this kind is experienced when electrodes are employed that are 20 impregnated with salts or similar substances which generate smoke when the electrodes are burned in the arc. I have discovered that this difficulty can be overcome by using an inclosure comprising several chambers 25 and by placing the arc in one of said chambers. When this arrangement is used the products of combustion settle as a precipitate or deposit remotely from the arc and the chamber surrounding the arc remains 30 clear. This arrangement I have described in Patent No. 975,935, granted to me November 15, 1910.

The present invention is an improvement over my previous invention. I find that I 35 can obtain the desired result by surrounding the arc with a substantially hemispherical or egg-shaped globe and arranging above it a chamber preferably of a flat parasol-like shape so that its walls are shaded from the 40 direct radiation of the arc.

The drawing represents a sectional elevation of a lamp constructed according to my invention and showing one embodiment thereof.

45 In the drawing, the usual casing *l* contains the mechanism for feeding the electrodes into the arc.

The top part of the casing is broken away as forming no part of my invention. The 50 electrodes *c c* protrude downward through the bottom of the casing *l* and converge toward the arc in this embodiment, which is adapted to arc-lamps in which the electrodes are both introduced from above and converge 55 toward the arc in the shape of a V. The inclosure *g* is shaped so as to form two cham-

bers, a lower chamber *b* which is substantially hemispherical and an upper chamber *a* preferably extending outward on all sides in a flat parasol shape so as to form a substantially horizontal flattened annular receptacle. In 60 operation, the result of this arrangement is that the smoke particles are effectually prevented from settling in the part where the walls are in proximity to the arc and are subjected to more or less normally impinging rays and are therefore precipitated in the part which by virtue of its shape is protected against any direct impact of the rays of light. By giving this latter part a shape as shown in the drawing, I obtain the further 65 advantage that it is adapted to act as a lamp shade, and also as a reflector. When it is desired to obtain a more perfect and constant reflection of the light from its walls, I make the latter of milky glass or of any 70 other suitable substance, such as, for instance, of enameled or polished metal.

Having thus described my invention, I claim as new and desire to secure by Letters 75 Patent:

1. An arc-lamp burning smoke-producing carbons, comprising a closed globe having in combination a substantially hemispherical chamber substantially concentric with the 80 arc and having all its parts in close proximity thereto, and a chamber having its outer part remote from the arc.

2. An arc lamp burning smoke producing carbons, comprising a chamber entirely 85 closed surrounding the smoke producing arc, having in combination, a substantially hemispherical globe substantially concentric to the position of the arc, and having all its parts in close proximity thereto, whereby it 90 is heated substantially equally throughout, and a condensing chamber having its outer part remote from the arc so as to cause a condensation therein.

3. An arc lamp burning smoke producing carbons, comprising an inclosure, surrounding the smoke producing arc and composed of two parts, a light transmitting part in close proximity to the arc and of a shape to be substantially equally heated, and a condensing part remote from the arc, and cooler than the proximate light transmitting part, and in free communication therewith, whereby the coolness causes condensation of the 95 gases produced by the arc, and the free communication causes further gases to enter the condensing part and to be condensed therein.

4. An inclosed smoke producing carbon arc-lamp comprising an arc inclosure having an arc-heated light-transmitting part in proximity to the arc and substantially 5 equally heated thereby, and a precipitation part disposed above said light-transmitting part and outspreading laterally therefrom substantially symmetrically therewith.

5. An inclosed smoke producing carbon 10 arc-lamp comprising an arc inclosure having a light-transmitting part subjected to the direct rays of the arc and substantially equally heated thereby, and a precipitation part disposed above said light-transmitting 15 part and having a laterally extended portion forming an annular flattened chamber distant from the arc and shaded from the direct radiation of the arc.

6. An inclosed smoke producing carbon 20 arc-lamp comprising an arc inclosure having an arc-heated light-transmitting part in close proximity to the arc and subjected to the direct rays thereof, and a precipitation receptacle of dominant size symmetrically 25 disposed above said light-transmitting part in free communication therewith and outspreading laterally therefrom forming a chamber laterally remote from said light-transmitting part and shaded from the direct rays of 30 the arc.

7. In an arc-lamp, the combination of a 35 closed globe, and a pair of carbons protruding downwardly therein and adapted to support an arc between their lower ends, said globe forming an approximately hemi-spherical chamber concentric with the arc and with all parts in close proximity thereto, and also an upper substantially horizontal flattened annular chamber merging into 40 the upper part of the hemi-spherical cham-

ber, the outer part of the annular chamber being remote from the arc.

8. In an arc lamp the combination of a substantially air tight closed globe, and a pair of converging carbons protruding downwardly through the upper part of the globe and adapted to support an arc between their lower ends, said globe forming about said arc an approximately hemi-spherical chamber concentric with said arc and every portion of which is in close proximity thereto, and also an upper flattened downwardly and outwardly inclined annular chamber merging into the upper part of the hemi-spherical chamber, the outer part of the annular chamber being remote from the arc. 45 50 55

9. In an arc lamp the combination of a substantially air tight closed globe, and a pair of converging carbons protruding downwardly through the upper part of the globe 60 and adapted to support an arc between their lower ends, said globe forming about said arc an approximately hemi-spherical chamber concentric with said arc and every portion of which is in close proximity thereto, and also an upper flattened downwardly and outwardly inclined annular chamber merging into the upper part of the hemi-spherical chamber, the outer part of the annular chamber being remote from the arc, the 65 70 lower part of the upper annular chamber being of non-transparent material.

In testimony, that I claim the foregoing as my invention, I have signed my name in presence of two subscribing witnesses.

TITO LIVIO CARBONE.
